REFRIGERATING MACHINE

René Joseph Emile Constant Vin, Paris, France,
assignor to Pierre Callon, Paris, FranceApplication June 9, 1933, Serial No. 675,134
In France June 11, 1932

4 Claims. (Cl. 62—115)

My invention relates to refrigerating machines adapted to operate on the usual compressing, condensing, expanding cycle and has for its object to provide a single unit apparatus of small size in which the lubricant which is brought forward by the refrigerating fluid during operation or when the apparatus is transported, may be rapidly and easily returned to the rotary parts.

Further objects of my invention will be set forth in the following description with reference to the accompanying drawings which are given solely by way of example and in which:

Fig. 1 is an elevational view, in section, of an apparatus in conformity with the invention.

Fig. 2 is a partial section, on a smaller scale, of a modified part of the arrangement shown in Fig. 1.

Figs. 3 and 4 are elevational views, with parts broken away, of two other embodiments.

In the form of construction represented in Fig. 1, the refrigerating machine is chiefly adapted for use with refrigerating fluids at low pressure, such as tetrachloride of carbon, ethyl chloride or the like. The compressor 1 is mounted in the interior of a cylindrical casing 2 and its shaft 3, which is located on the vertical axis of said casing, is driven at its end, which is provided with a tight coupling, by a pulley 5, but it might also be driven by a motor mounted on the end of the shaft. The said compressor draws through a conduit 7 the gas from an expansion chamber 8 secured to the casing 2. The compressed gas is delivered through a conduit 9 into a cylindrical duct 10 located at the centre of a condensation chamber 12. The lower end of said duct is situated at a short distance from the bottom 13 of the condensation chamber 12 and it forms with the lateral wall of said chamber an annular space 14. Spiral tubes 15 for condensation, in which water or other cooling liquid is circulated, are mounted in said annular space 14 and are preferably situated in such way that the coils will alternately rise and descend, as shown by the arrows. The cooling liquid is circulated in the spiral tubes 15 by means of a pump or the like, not shown, and its output can be regulated, automatically or not, according to needs.

A pipe 17 which is practically coaxial with the duct 10 connects the lower part of the condensation chamber 12 with a bore 18 formed in the compressor shaft and which communicates through apertures 19 with the parts to be lubricated.

A cock 22 is mounted at the upper part of the chamber 12 for filling purposes.

An overflow conduit 23 connects the condensation chamber 12 with an intermediate chamber 24 located below this latter and in the interior of the expansion chamber 8. The connection between the chambers 24 and 8 is assured by an orifice 25 whose flow section is controlled by a balanced float 26 mounted in the expansion chamber 8.

The expansion chamber 8 has a practically conical form, with the small end downward, and communicates at the small end and at the upper end with the respective ends 29 and 30 of a cooling spiral pipe 31. The orifice 29 for the entrance of the cooling fluid into the spiral pipe 31 is preferably surrounded by a cup 32 adapted to retain any traces of lubricant which may be drawn forward.

The entire apparatus is pivoted about a horizontal axis, which arrangement is represented by two trunnions 35 secured to the casing 2.

The operation is as follows:

The cooling fluid drawn into the chamber 8 is delivered through the conduit 8 into the duct 10 which serves to separate the lubricant. This latter collects at the lower part of the chamber 12, whence it returns to the rotary parts to be lubricated through the pipe 17 into which it is forced simply by the effect of the pressure prevailing in the chamber 12.

As the liquid in the chamber 12 forms a joint 30 between the bottom 13 of this chamber and the lower end of the duct 10, the compressed gas is obliged to rise and to proceed into the annular space 14, in which it is condensed by the tubes 15. The resulting liquid, which is lighter than the lubricant, accumulates in the lower part of the chamber 12, above the layer of lubricant, and flows into the intermediate chamber 24 through the overflow conduit 23.

The refrigerating liquid passes thence into the expansion chamber 8 through the orifice 25 controlled by the float 26 and circulates in the tube 31 into which it enters through the aperture 29 and in which it produces the desired cooling effect.

The traces of lubricant which may be carried beyond the condensation chamber 12 by the refrigerating liquid or during the transportation of the apparatus can be returned very simply into its work circuit, when desired, by pivoting the whole apparatus above the horizontal axis represented by the trunnions 35.

In the form of construction represented in Fig. 2, the orifice 25 connecting the intermediate chamber 24 with the expansion chamber 55

8 is also provided with an overflow tube 37, which further reduces the amount of lubricant drawn into said chamber 8. On the other hand, the said chamber 8, in which the 5 intermediate chamber is formed by means of a wall, is quite distinct in its construction from the rest of the apparatus and is secured to the latter by a bolt 38.

Fig. 3 relates to an arrangement which is particularly advantageous when it is desired to cool 10 a refrigerating chest or the like of small size. The motor part 39 and the high-pressure chamber 12 are mounted at the exterior of a door 40 and communicate through the pipes 7 and 25 15 with a unit device comprising an expansion chamber 8 containing an intermediate chamber 24, and the cooling tubes 31. The door 40 is pivotally mounted on a horizontal axis 41, and thus the lubricant may be again brought into 20 the work circuit, as above set forth with reference to Fig. 1. Fig. 3 also shows the cooling worm-tubes 31 which are provided with flanges 42 by which the cold is diffused.

Fig. 4 represents the high-pressure part of an 25 apparatus, in which the cooling required for the condensation of the gases is effected by means of atmosphere air. In this construction, the vapour drawn by the pipe 7 from the expansion chamber, not shown, is delivered into a flanged 30 spiral tube 45 in which it is condensed before it is delivered into the condensation chamber 12 through the pipe 9.

The lubricant returns from this chamber to the movable parts through the pipe 17 and the 35 refrigerating liquid is discharged through the overflow 23, as in the preceding constructions.

The spiral tubes 45 are located in an annular space 46 in the casing 2 in which the air is circulated from the lower apertures 47 to the upper 40 apertures 48 by means of an air-fan 49 mounted on the shaft of the compressor 1. The whole apparatus can be pivoted on the trunnions 35.

While I have described what I at present consider preferred embodiments of my invention, it 45 will be obvious to those skilled in the art that various changes and modifications may be made without departing from my invention and I, therefore, aim in the appended claims to cover all such changes and modifications as fall within 50 the true spirit and scope of my invention.

I claim:

1. In a refrigerating machine adapted to operate on the usual compressing, condensing, expanding cycle, the combination of a gas com-

pressor, means for driving said compressor, a condensing chamber, a substantially cylindrical duct within said chamber defining with the lateral surface of said partition an annular space the lower part of which is in communication with the lower part of said duct, condensing means located in said annular space, means for delivering the lubricating oil carrying compressed gas into said duct, wherein oil is mechanically separated from the gas, means for returning to the parts of said compressor to be lubricated said separated oil, said means comprising a pipe, connecting the lower part of said chamber with the compressor so that oil will be forced to said parts through said pipe by the pressure prevailing in said chamber.

2. In a refrigerating machine adapted to operate on the usual compressing, condensing, expanding cycle, the combination of a compressor, means for driving said compressor, a condensing chamber, means for delivering into said condensing chamber the oil containing compressed gas issuing from said compressor, condensing means for said compressed gas, whereby it is formed above the bottom of said condensing chamber a layer of oil covered by a layer of condensed gas, means for returning said oil to the parts of the compressor to be lubricated, an intermediate chamber, a pipe connection between said condensing and intermediate chambers, said connection issuing above the bottom of said condensing chamber, an expansion chamber connected with said intermediate chamber and said compressor, and means for rotatably supporting as a whole said chambers and said compressor, in such a manner that they may be swung about a substantially horizontal axis, thus allowing the lubricating oil drawn beyond said condensing chamber to return to the latter.

3. A refrigerating machine as claimed in claim 40 2 wherein said intermediate chamber is mounted below said condensing chamber, and above said expansion means, said condensing chamber being itself mounted below said compressor.

4. A refrigerating machine as claimed in claim 43 2, wherein said rotatably supporting means comprises a support, rotatably mounted about a substantially horizontal axis, said compressor and condensing chamber being fixed on one side of said support, and said intermediate chamber and 50 expansion means on the other side.
